UNITED STATES PATENT OFFICE.

JOHN H. DEUTSCH, OF DE BERRY, TEXAS, ASSIGNOR OF ONE-HALF TO J. T. STRANGE, OF ELYSIAN FIELDS, TEXAS.

PIANO-ACTION.

No. 854,280.

Specification of Letters Patent.

Patented May 21, 1907.

Application filed July 30, 1906. Serial No. 328,421.

To all whom it may concern:

Be it known that I, JOHN H. DEUTSCH, a citizen of the United States, residing at De Berry, in the county of Panola and State of Texas, have invented new and useful Improvements in Piano-Actions, of which the following is a specification.

My invention pertains to piano actions; and it contemplates the provision of means for effecting a strong and durable connection between the bridle strap and the hammer butt of a piano action, and this without resort to the employment of glue or other adhesive substance which is objectionable because it increases the chances of the bridle strap being cut through by vermin after a short period of use.

The invention will be fully understood from the following description and claims when the same are read in connection with the accompanying drawings, forming part of this specification, in which:

Figure 1 is a side elevation of so much of a piano action as is necessary to illustrate the application of my improvement. Fig. 2 is an enlarged detail section taken longitudinally through the shank on the hammer butt and illustrating the relative arrangement of the said shank, the bridle strap and the bridle strap fastener. Fig. 3 is a transverse section taken through the tongue of the fastener. Fig. 4 is an enlarged perspective view illustrating the bridle strap and the fastener properly arranged relative to each other.

Similar letters designate corresponding parts in all of the views of the drawings, referring to which:

A is the hammer butt of a piano action from which extends the usual countercheck a.

B is the jack lever of the action, provided with the usual rod b.

C is the ordinary bridle strap connected to the rod b, and D is my novel fastener for effecting connection between the bridle strap and the countercheck of the hammer butt. The said fastener D comprises a split ring c, of spring steel or other material suitable to the purpose of my invention, having a cross-wise slot d in its lower portion and upturned flanges e on its ends and also having a tongue f struck up from the ring and joined at one end thereto and provided with one or

more depending barbs or projections g, and bolts h for connecting the flanges on the ends of the split ring c.

In the practical application of my improvement, the bridle strap C is drawn under the tongue f in such manner that said strap rests between the tongue above and the side walls of the slot d below, Fig. 2, after which the ring c is opened to receive the countercheck a on the hammer butt A and is fastened on said countercheck through the medium of the screws h. With the parts positioned as stated and as best shown in Figs. 2 and 3, the bridle strap C will obviously be securely held by the tongue f and between said tongue and the lower portion of the ring c without liability of said strap being pulled away or otherwise casually disconnected from the butt shank. It will also be apparent that the connection is susceptible of being quickly and easily made, and does not entail the employment of glue or other adhesive substance which latter is objectionable since it renders the bridle strap liable to be cut through by vermin.

It will be gathered from the foregoing that my novel fastener is simple and compact, and that when nickel-plated or otherwise embellished it will enhance rather than detract from the finished appearance of the action.

The construction shown and described constitutes the preferred embodiment of my invention, but I do not desire to be understood as confining myself to such construction inasmuch as such changes or modifications may be made in practice as fairly fall within the scope of my invention as claimed.

Having described my invention, what I claim and desire to secure by Letters-Patent, is:

1. In a piano action, the combination of a hammer butt provided with a countercheck, a bridle strap, and a fastener comprising a ring secured on the countercheck and having a tongue; the said ring receiving the bridle strap between its tongue and main portion.

2. In a piano action, the combination of a hammer butt provided with a countercheck, a bridle strap, and a fastener comprising a ring secured on the countercheck and having a slot in its lower portion and a barbed

tongue struck up from said portion; the said ring receiving the bridle strap between its tongue and lower portion.

3. In a piano action, the combination of a hammer butt provided with a countercheck, 5 a bridle strap, and a fastener comprising a split ring mounted on the countercheck and having detachably connected end flanges and also having a slot in its lower portion and a 10 barbed tongue struck up from said portion; the said split ring receiving the bridle strap between its tongue and lower portion.

4. In a piano action, the combination of a hammer butt provided with a countercheck, 15 a bridle strap, and a fastener secured on the

countercheck and having a tongue; the said fastener receiving the bridle strap between its tongue and main portion.

5. As an article of manufacture, a split ring having means for connecting its end portions together and also having a slot in its intermediate portion and an integral tongue formed by said slot. 20

In testimony whereof I have hereunto set my hand in presence of two subscribing witnesses. 25

JOHN H. DEUTSCH.
